UNITED STATES PATENT OFFICE.

CHARLES L. McCUEN, OF CHICAGO, ILLINOIS, ASSIGNOR, BY MESNE ASSIGNMENTS, TO
DELCO-LIGHT COMPANY, OF DAYTON, OHIO, A CORPORATION OF DELAWARE.

REFRIGERATING APPARATUS.

Application filed August 5, 1920. Serial No. 401,426.

To all whom it may concern:

Be it known that I, CHARLES L. McCUEN, a citizen of the United States, residing at Chicago, in the county of Cook and State of Illinois, have invented certain new and useful Improvements in Refrigerating Apparatus, of which the following is a specification.

My invention relates to a refrigerating apparatus of that type in which a refrigerant, such as sulphur dioxide, is used and the object thereof is to provide a novel, efficient and compact structure for the pump chamber and condenser chamber. The various features of advantage and utility in my structure will be apparent from the description hereinafter given.

In the drawings, Fig. 1 is a central vertical sectional elevation through my structure; Fig. 2 a top plan view thereof; and Fig. 3 an end elevation.

My new structure comprises essentially a casing 1 having formed therein a pump chamber 2 and a condenser chamber 3, a pump 4 and an electric motor 5 for actuating such pump. The casing which is here an integral structure or single casting is provided at one end and in its lower portion with an opening 6 through which is inserted the pump structure 4. The structure is provided with a marginal flange 7 which is secured to the casing 1 by means of the screws 8. This pump may be of any suitable type and construction but I prefer the type shown in the drawings, which is substantially the same as that illustrated and described in Leonard Patent No. 1,233,069, issued July 10, 1917. My present invention, however, is independent of the particular character or construction of the pump. The armature shaft 9 of the electric motor 5 is operatively connected with the driving shaft 10 of the pump whereby the latter is driven as explained in said patent.

As shown particularly in Fig. 1, and by preference, the motor is mounted upon a supporting plate 11, which is secured to the casing 1 by the same bolts 8 which secure the flanges 7 thereto. The motor is secured to said support in a suitable manner as by means of the screws 12.

The delivery port 13 of the pump connects with a vertical delivery pipe 14 which extends upwardly into the upper portion of the pump chamber. At its upper end this

pipe is provided with a collector plate or basin 15 so as to catch any condensed gas that may enter it from the superimposed baffle plate 16 depending from the upper end of the pump chamber.

The pump chamber is closed except for the discharge outlet 17 by means of a plate 18 which is secured to the top of the casting 1, by means of the screws 19, 19', and properly sealed at the points of connection. The baffle plate 16 is secured to or forms a part of a horizontal plate 20, which is in turn secured to the plate 18 by rivets 21 or otherwise. This plate 20 has a central opening which constitutes said outlet 17 and the central portion of the plate is crimped and bent at its center in the form shown in Fig. 1, so as to afford strength and also a suitable seat for the hand operated valve 22, which is here shown in a position closing said outlet. After removing the cap 23 and using a socket wrench upon the valve stem 24 which is screw threaded into the plug 23^a the valve may be withdrawn from its seat at the outlet 17. In the present instance, I provide this valve with a double seat, one at the outlet 17 and the other at 23^b on the lower end of the plug. This avoids the necessity of a packing gland, as the valve when opened rests against the upper seat. The particular function of this valve is to prevent exchange of oil over to the condenser chamber during shipment.

This controlling valve 22 is mounted in a top plate 25, which is secured to the casting 1 by the same screws 19, hereinbefore described, and also by the screws 26. The plate 18 extends not only over the pump chamber but over the condenser chamber and the same is provided with a large opening coincident with such condenser chamber. This opening has an upwardly extending flange 27, adapted to receive the downwardly extending flange 28 of a condenser cylinder 29 which depends from said flange 27 to near the bottom of the condenser chamber. This cylinder is of somewhat less diameter than the condenser chamber, with the result that an annular chamber 30 is formed between its outer walls and the inner walls of the condenser chamber. This annular chamber is for the purpose of providing a water-cooling circulation which may be admitted at any suitable point, as at 31, and released at any other suitable point, 110

as at 32. As the gas is compressed by and delivered from the pump 4, it passes upwardly through the pipe 14 into the upper portion of the pump chamber from whence it 5 escapes through the outlet 17, passing horizontally above the plate 18 and thence downwardly into the condenser cylinder 29, wherein it is condensed. The refrigerant, which is now a liquid cooled in the bottom of the 10 cylinder 29, passes upwardly through the vertical draw-off pipe 33, which extends upwardly, and is connected to the pipe fitting 34, which in turn is secured to the plate 25. The refrigerant then passes through a suitable 15 needle valve 35 and thence through the pipe 36 to the remainder of the refrigerating system, such as expansion valve and refrigerating coils, which, being of the usual and well-known type, need not be illustrated or described. The function of the 20 valve 35 is to retain the refrigerant in the condensing cylinder during shipment and to provide an easy means of connecting the refrigerant line to the expansion system at the 25 time of installation and also an easy means of removal of machine.

The pump chamber wall adjacent the condenser chamber and separating such pump chamber from the cooling space 30 which 30 wall is preferably provided with fins 37, causes a cooling of the oil surrounding the pump, inasmuch as the condensing water in said space acts through such wall and fins to thus cool the oil.

35 I claim:

1. In a refrigerating apparatus of the class described, the combination of a casing having therein a pump chamber and a condenser chamber arranged parallel to each other, a pump in the pump chamber, a plate secured to the top of the casing and having an outlet opening from the pump chamber and an inlet opening into the condenser chamber, a condenser cylinder secured to said plate at said inlet opening, said cylinder being open at its top and closed at its bottom, means for conducting the liquid refrigerant from the cylinder, and a cover secured to the casing and above the plate to 50 form a gas passage between them.

2. In a refrigerating apparatus of the class described, the combination of a casing having therein a pump chamber and a condenser chamber arranged parallel to each other, a pump in the pump chamber, a plate secured to the top of the casing and having an outlet opening from the pump chamber and an inlet opening into the condenser chamber, a condenser cylinder secured to said plate at said inlet opening, said cylinder being open at its top and closed at its bottom, means for conducting the liquid refrigerant from the cylinder, said plate at its inlet opening and said cylinder at its top 60 edge having interlocking flanges whereby

the cylinder is suspended from the plate, and a cover secured to the casing and above the plate to form a gas passage between them.

3. In a refrigerating apparatus of the class described, the combination of a closed casing having therein a pump chamber and a condenser chamber arranged parallel to each other, a pump in the pump chamber, a plate secured within the casing and having an outlet opening from the pump chamber and an inlet opening into the condenser chamber, a condenser cylinder secured to said plate at said inlet opening, said cylinder being open at its top and closed at its bottom and a cover secured to the casing and above the plate to form a gas passage between them, means for conducting the liquid refrigerant from the cylinder, said cylinder being of less diameter than the condenser chamber so as to form an annular space for water cooling circulation.

4. In a refrigerating apparatus of the class described, the combination of a casing having therein a pump chamber and a condenser chamber arranged parallel to each other, a pump in the pump chamber, a plate secured to the top of the casing and having an outlet opening from the pump chamber and an inlet opening into the condenser chamber, a condenser cylinder secured to said plate at said inlet opening, said cylinder being open at its top and closed at its bottom and a cover secured to the casing and above the plate to form a gas passage between them, means for conducting the liquid refrigerant from the cylinder consisting of a vertical pipe extending through the inlet opening and into the cylinder to near the bottom thereof.

5. In a refrigerating apparatus of the class described, the combination of a casing having therein a pump chamber and a condenser chamber arranged parallel to each other, a pump in the pump chamber, a plate secured to the top of the casing and having an outlet opening from the pump chamber and an inlet opening into the condenser chamber, a condenser cylinder secured to said plate at said inlet opening, said cylinder being open at its top and closed at its bottom, means for conducting the liquid refrigerant from the cylinder, consisting of a vertical pipe extending through the inlet opening and into the cylinder to near the bottom thereof, and a cover secured to the casing and above the plate to form a gas passage between them, the pipe being secured to and depending from the cover.

6. In a refrigerating apparatus of the class described, the combination of a casing having therein a pump chamber and a condenser chamber arranged parallel to each other, a pump in the pump chamber, a plate secured to the top of the casing and having

an outlet opening from the pump chamber and an inlet opening into the condenser chamber, a condenser cylinder secured to said plate at said inlet opening, said cylinder being open at its top and closed at its bottom, means for conducting the liquid refrigerant from the cylinder, a cover secured to the casing and above the plate to form a gas passage between them, and gas valve mounted in said cover and controlling said outlet from the pump chamber.

7. In a refrigerating apparatus of the class described, the combination of a casing having therein a pump chamber and a condenser chamber arranged parallel to each other, a pump in the pump chamber, a plate secured to the top of the casing and having an outlet opening from the pump chamber, a condenser cylinder within the condenser chamber and connected with the casing adjacent the top thereof, said cylinder being open at its top and closed at its bottom, means for conducting the liquid refrigerant from the cylinder, and a cover secured to the casing and above the plate to form a gas passage between them.

8. In a refrigerating apparatus of the class described, the combination of a casing having therein a pump chamber and a condenser chamber separated by a wall, a pump in the bottom of the pump chamber, such latter chamber being adapted to contain a body of oil in which the pump is submerged, said wall having fins in said body of oil, a condenser cylinder arranged in the condenser chamber to form an annular cooling space between it and the condenser cylinder including said wall, whereby a cooling medium in such space acts through the wall and fins to cool the body of oil.

9. In a refrigerating apparatus of the class described, the combination of a casing having therein a pump chamber and a condenser chamber arranged along one side of the pump chamber separated therefrom by a common wall, a pump in the pump chamber spaced from said common wall and submerged in a fluid, and means for circulating a cooling medium in the condenser chamber whereby heat is abstracted through the common wall to cool the pump chamber.

10. In a refrigerating apparatus of the class described, the combination of a casing

having therein a pump chamber and a condenser chamber arranged along one side of the pump chamber separated therefrom by a common wall, a pump in the pump chamber spaced from said common wall and submerged in a fluid, and means for circulating a cooling medium in the condenser chamber in contact with the common wall whereby heat is abstracted through the common wall to cool the pump chamber.

11. In a refrigerating apparatus of the class described, the combination of a casing having therein a pump chamber and a condenser chamber arranged parallel to each other, a pump in the pump chamber, a plate secured to the top of the casing and having an outlet opening from the pump chamber and an inlet opening into the condenser chamber, a cover secured to the casing and above the plate to form a gas passage between the chambers, and a valve member carried by the cover and adapted to seat on the plate to close the said opening therein.

12. In a refrigerating apparatus of the class described, the combination of a casing having therein a pump chamber and a condenser chamber arranged parallel to each other, a pump in the pump chamber, a plate secured to the top of the casing and having an outlet opening from the pump chamber and an inlet opening into the condenser chamber, a cover secured to the casing and above the plate to form a gas passage between the chambers, and a valve member carried by the cover and adapted to seat on the plate to close the said opening therein, said valve being adjustable from the exterior of said apparatus.

13. In a refrigerating apparatus of the class described, the combination of a casing having therein a pump chamber and a condenser chamber arranged parallel to each other, a pump in the pump chamber, a plate secured to the top of the casing and having an outlet opening from the pump chamber and an inlet opening into the condenser chamber, a cover secured to the casing and above the plate to form a gas passage between the chambers, and a valve member traversing the passage and adapted to seat on the plate to close the said opening therein.

CHARLES L. McCUEN.
